UNITED STATES PATENT OFFICE.

JOSIAH A. VAN BRUNT, OF RUTHERFORD, NEW JERSEY.

DESIGN FOR A BATH THERMOMETER.

Application filed March 30, 1928. Serial No. 26,078. Term of patent 14 years.

To all whom it may concern:

Be it known that I, JOSIAH A. VAN BRUNT, a citizen of the United States, and resident of Rutherford, in the county of Bergen and State of New Jersey, have invented a new, original, and ornamental Design for a Bath Thermometer, of which the following is a specification, reference being had to the ac-

companying drawing, forming part hereof.

Fig. 1 is a plan view of a bath thermometer showing my new design, and Fig. 2 is a side elevation thereof.

I claim:

The ornamental design for a bath thermometer as shown.

JOSIAH A. VAN BRUNT.
